US00D694628S

(12) **United States Design Patent**
Matsumoto et al.

(10) **Patent No.:** US D694,628 S
(45) **Date of Patent:** ** Dec. 3, 2013

(54) **CONTAINER CONFIGURATION**

(75) Inventors: **Tamotsu Matsumoto**, Chiba (JP);
Makiko Kida, Chiba (JP); **Takuma Watanabe**, Tokyo (JP); **Evan Abel**, Rockaway Park, NY (US)

(73) Assignee: **Helen of Troy Limited**, St. Michael (BB)

(**) Term: **14 Years**

(21) Appl. No.: **29/430,266**

(22) Filed: **Aug. 23, 2012**

(51) **LOC (9) Cl.** 07-01

(52) **U.S. Cl.**

USPC **D9/505**; D7/629; D7/701; D7/614

(58) **Field of Classification Search**

USPC D7/628, 629, 505, 506, 538, 602, 701, D7/614, 706, 566, 501; D9/430, 743, 745; 220/23.83, 792, 793, 234

Primary Examiner — Marianne Pandozzi

(57) **CLAIM**

The ornamental design for a container configuration, as shown and described.

DESCRIPTION

FIG. 1 is a perspective view of the container configuration; FIG. 2 is a top view of the container configuration; FIG. 3 is a front view of the container configuration; FIG. 4 is a side view of the container configuration; and, FIG. 5 is a bottom view of the container configuration. The broken lines are for illustrative purposes only and form no part of the claimed design.
